SHOE WITH METATARSAL SUPPORT AND
METHOD OF MAKING SAME

Oliver E. De Ridder, Rochester, N. Y.

Application July 5, 1933, Serial No. 679,119

5 Claims. (Cl. 12—142)

The invention relates to a shoe of the turned shoe or the stuck on shoe type and method of making the same.

The object of the present invention is to incorporate in a shoe, such as a turned shoe or a Sbicca shoe of Patent No. 1,902,725, a support for the metatarsal joint as well as the main arch of the foot and to enable a shank piece divided from the single sole and extending from the heel to the metatarsal joint to be molded on a last constituting the female member of the mold and on which the shoe is lasted so that it will be unnecessary for the shank piece after being molded, to be removed from the last, and the metatarsal support by being incorporated in the shoe in the manufacture thereof will always remain in proper position.

Heretofore attempts have been made after a shoe of the said type has been constructed to apply to such a shoe a metatarsal support as an auxiliary part or accessory secured to the completed shoe in an effort to fit the requirements of the wearer. Such attempts have been unsatisfactory because shoes have always been made with a flat bottom and owing to construction difficulties when a shoe or insole is tampered with it loses its true contour or shape around the edges and a shoe to which such an auxiliary device has been applied would not have its true form.

All shoes have to be made over a last and any construction which interferes with the bottom shape of that last produces a malformation of the shoe. The ideal of many shoe manufacturers for years has been to try and mold the conformation of the bottom of the foot into a shoe which would save the person from doing what is called "breaking in" a shoe. By this molding process, such as is described in Patent No. 1,479,899, granted to me January 8, 1924, the molding of an inner sole was accomplished by using a last as the female member of the mold. By employing the last mold and metatarsal support in the shank piece of a single sole shoe, a shoe having a metatarsal support is produced without distorting the insole or interior of the shoe as is the case where the metatarsal support is applied as a separate piece or accessory to the shoe after the lasting of the same has been completed.

All shoes to be practical must have a flat bottom on the outside for if any protrusions were on the bottom of the shoe they would simply wear off. If a single sole of the ordinary construction used in the aforesaid type of shoes were molded on a last there would be formed on the bottom of the single sole projections which would soon wear

off and destroy the metatarsal supporting character of such a single sole. By the present method the shank piece divided from the single sole blank and constituting an inner sole or inner section of a single sole is supported at the molded arched metatarsal joint supporting portion by a resilient filler located below the front end of the shank piece and interposed between the shank piece and the outer section of the single sole blank.

This will support the arch of the shank piece and enable the sole to have a flat bottom. The molding of the metatarsal supporting shank piece by the last on which the shoe is lasted will give shoes a foot print in leather and will obviate the necessity of breaking in a shoe.

With these and other objects in view, the invention consists in the construction and novel combination and arrangement of parts herein-after fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Fig. 1 is a perspective view of a last having a depression for molding in the shank piece of a shoe a metatarsal support.

Fig. 2 is a similar view showing an insole section divided from a single sole blank applied to the last, the rand being split from the free front spatulate portion or flap of the shank piece.

Fig. 3 is a perspective view of the last and the inner sole ready to have the upper of the shoe and the outer sole lasted or applied to the inner sole.

Fig. 4 is a longitudinal sectional view on the line 4—4 of Fig. 3.

Fig. 5 is a transverse sectional view on the line 5—5 of Fig. 3.

Fig. 6 is a detail perspective view of the outer sole after the shank piece and the rand have been divided therefrom.

Fig. 7 is a longitudinal sectional view through the completed shoe.

Fig. 8 is a transverse sectional view of the same.

Fig. 9 is a perspective view of the last and a shank piece divided from a single sole blank and constituting the inner sole.

Fig. 10 is a similar view of the outer sole, the shank piece being divided therefrom.

Fig. 11 is a longitudinal sectional view of a complete shoe having the shank piece constituting the inner sole.

Fig. 12 is a transverse sectional view of the same.

Fig. 13 is a detail perspective view of an elastic pad or filler.

5 In the accompanying drawings in which is illustrated the preferred embodiments of the invention, 1 designates a last constituting the female member of a mold in a manner set forth in the aforesaid patent and provided in its bottom 10 or lower sole receiving face with a depression 2 adapted to mold in the front end of a shank piece 3 a raised or arched portion 4 to form a metatarsal support or a support for the metatarsal joint of the foot of the wearer. The shank piece 15 3 which is divided from an outer sole 5 may be formed integral with a rand 6, as illustrated in Figs. 2 and 3 of the drawings, but the said last 1 may be used for molding a metatarsal support 7 in a shank piece 8 without a rand, as illustrated 20 in Figs. 9 to 12 inclusive of the drawings, when the single sole shoe consists only of a single sole and a shank piece.

The rand which is formed integral with the shank piece is partially split from the same, as 25 clearly illustrated in Fig. 2 of the drawings, and the partial splitting of the rand provides a free front end or flap 3^a for the shank piece to enable the metatarsal support to be molded therein.

The shank piece 3 which extends from the 30 heel to the metatarsal joint of the foot is provided with the free front end or flap 3^a of spatulate formation which is arched by the mold to form the metatarsal support 4. The shank piece which is moistened for molding is secured to the 35 last in the usual manner and a resilient filler 9 of any suitable material is arranged below the arched metatarsal support of the spatulate front end of the shank piece to retain the support in its rounded protruding shape and enable the 40 outer sole to present a flat lower face. The pad or filler which is secured in place by cement has a rounded upper face and a flat lower face, the upper face being curved both longitudinally and transversely of the shoe.

45 After the resilient pad or filler is placed in position the rand 6 is moved from the folded back position illustrated in Fig. 2 of the drawings, to its normal or proper position on the front portion of the last, as illustrated in Fig. 3 of the drawing, 50 and the inner sole or inner section of the single sole is molded as explained in the aforesaid patent, and after molding it is unnecessary to remove the inner sole, formed by the shank piece and the rand from the last and the outer sole 5 55 and the upper 10 are lasted or applied to the inner sole and the latter is incorporated in the shoe in the construction thereof so that the protruding metatarsal support 4 is formed or provided in the shoe in the construction thereof and will 60 always remain in proper position.

Also by the formation of the metatarsal support in the shank piece during the construction of the shoe the form or contour of the shoe at the edges of the sole is not altered or in any 65 wise affected as is the case when after a shoe is constructed a metatarsal support is applied to the shoe as an accessory or as an attachment. In the lasting of the shoe the upper and the inner and outer soles are secured together by 70 cementing, but any other suitable means may, of course, be employed as will be readily understood. A complementary insole-outsole combination is made from a single sole blank without any waste.

75 The shoe having the shank piece and the in-

tegral rand divided from the outer sole and the method of forming the same are illustrated in Figs. 1 to 8 inclusive of the drawings. The shoe having the inner sole consisting solely of the shank piece 8 divided from the outer sole 11 is illustrated in Figs. 9 to 12 inclusive of the drawings. The shank piece 8 which constitutes the inner sole is molded on the last 1 and a filler or pad 12 is placed between the metatarsal support 7 and the outer sole to preserve the configuration of the arched metatarsal support 7 of the shank piece 8. The shank piece 8 is molded as heretofore described in accordance with the method explained in the aforesaid patent and the outer sole 11 with its reduced portion 13 and 15 the shank piece 8 constitute a single sole. In the lasting of the shoe the upper 14 is lasted around the shank piece 8 and the latter constitutes a portion of the shoe and is incorporated in the same during the construction of the shoe 20 and as it is not removed from the last 1 on which the shoe is lasted it will by being incorporated in the shoe as a structural portion thereof, always maintain the metatarsal support in proper 25 position.

The pad or filler is of sponge rubber, or any other suitable material may, of course, be employed, and the last 1 having depressions or tapered concavities of various sizes and shapes may be provided to form a metatarsal support 30 of the desired size and curvature both longitudinally and transversely of the shoe. Irrespective of the length and width of the single sole of the shoe, the metatarsal pad may be properly positioned with relation to the sole of 35 the shoe and the shank of leather because of grading, that is, because of various sizes of soles and shanks. For instance, in a size 5 the sole and shank would be longer than the sole and shank of a number 4 shoe. The metatarsal support 40 which is formed by molding the shank piece at the spatulate front end thereof is curved both longitudinally and transversely of the shoe and depressions are formed at the sides of the raised protrusion or portion which constitutes the metatarsal support and a shoe provided with a metatarsal support has the same in proper position and is partially if not wholly broken in and does not require the breaking in of a single sole 45 shoe as is necessary with single sole shoes of 50 the ordinary construction.

What is claimed is:

1. A shoe having a shank piece complementary to the sole of said shoe and extending from the heel to the ball and having a spatulate front end provided with a molded, arched metatarsal supporting portion, and a rand also complementary to the sole and connected with the shank piece in rear of the spatulate front end thereof.

2. A shoe having a shank piece complementary to the sole of said shoe and extending from the heel to the ball and having a spatulate front end provided with a molded arched metatarsal supporting portion and a rand also complementary to the sole and connected with the shank piece in rear of the spatulate front end thereof.

3. The method of making a shoe with a shank piece having a rand extension and a flap portion at its front end which consists in securing the shank piece to a last having a depression, and molding in the free front end portion of the shank piece a metatarsal support by means of the said depression, and lasting an upper to the shank piece and the rand without removing the same from the last to incorporate the shank piece 75

and the rand in the shoe during the construction thereof.

4. The method of making a shoe with a shank piece having a rand extension and a flap portion at its front end which consists in securing the shank piece to a last having a depression and molding in the free front end portion of the shank piece a metatarsal support by means of the said depression, inserting a resilient pad beneath the 10 metatarsal supporting portion of the front end of the shank piece between the latter and the rand, and lasting an upper to the shank piece and

the rand without removing the same from the last to incorporate the shank piece and the rand in the shoe during the construction thereof.

5. A shoe of the class described including a shank piece having an integral front flap and provided with an integral rand extension connected with the shank piece at the inner end of the front flap, a cushion arranged between the front flap and the inner portion of the rand extension, and a complementary outer sole fitting the shank piece and the rand extension.

and the rand in the shoe during the construction thereof.

4. The method of making a shoe with a shank piece having a rand extension and a flap portion at its front end which consists in securing the shank piece to a last having a depression and molding in the free front end portion of the shank piece a metatarsal support by means of the said depression, inserting a resilient pad beneath the 10 metatarsal supporting portion of the front end of the shank piece between the latter and the rand, and lasting an upper to the shank piece and

the rand without removing the same from the last to incorporate the shank piece and the rand in the shoe during the construction thereof.

5. A shoe of the class described including a shank piece having an integral front flap and provided with an integral rand extension connected with the shank piece at the inner end of the front flap, a cushion arranged between the front flap and the inner portion of the rand extension, and a complementary outer sole fitting the shank piece and the rand extension.
